SURGICAL CAST CUTTER

Clarence R. Cummins, 831 W. 23rd St., Erie, Pa., assignor of forty percent to Thomas B. Dempsey, Erie, Pa.

Filed Jan. 29, 1962, Ser. No. 68,563

Term of patent 14 years

(Cl. D83—12)

FIG. 1

FIG. 2

FIG. 1 is a perspective view of a surgical cast cutter showing my new design; the undisclosed side is substantially the same in appearance; and

FIG. 2 is a fragmentary front elevation thereof, the undisclosed rear being plain and conically shaped.

It is to be understood that the teeth on the circular saw blade continue throughout the broken line area. The electric cord is fragmentarily shown for convenience of illustration.

I claim:

The ornamental design for a surgical cast cutter, as shown and described.
